UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL.

Specification forming part of Design No. 6,391, dated February 11, 1873.

To all whom it may concern:

Be it known that I, FREDERICK WINK, of the city and county of Philadelphia, State of Pennsylvania, have invented a Design for a Shawl-Pattern, of which the following is a specification:

The figure in the accompanying drawing fully represents my design, the main feature of which is the stripe A, the latter being repeated throughout the pattern.

The stripe A is composed of a series of parallel minor stripes or ribs, a, b, c, d, e, f, g, h, and i, of which all but the stripes b and h consist of single plain ribs or combinations of such ribs. The stripe b is of a highly ornamental character, it having at each side an ornamental edging, and an elaborate center composed of dots, transverse bars, and longitud-

inal bars blended together by shading and reduced to points, all of which is too clearly shown in the drawing to need description. The stripe h is of the same general character as the stripe b, except that it is narrower.

Irrespective of the colors employed, I claim—

1. The design for the minor stripe b, as represented.
2. The design for the whole pattern, as shown.

In testimony whereof I have signed my name to this specification in the presence of two subscribing witnesses.

FRED. WINK.
